UNITED STATES PATENT OFFICE.

JOSEPH SONNENBERG, OF IRVINGTON, NEW JERSEY.

COMBINED DOOR KNOB AND LOCK.

Application filed October 29, 1924. Serial No. 746,485.

To all whom it may concern:

Be it known that I, JOSEPH SONNENBERG, a citizen of the United States, residing at Irvington, in the county of Essex and State 5 of New Jersey, have invented certain new and useful Improvements in Combined Door Knobs and Locks; and I do hereby declare the following to be a full, clear, and exact description of the invention, such as will enable others skilled in the art to which it 10 pertains to make and use the same, reference being had to the accompanying drawings, and to characters of reference marked thereon, which form a part of this specification.

15 This invention relates, generally, to improvements in combination door-knobs and locks; and, the present invention has reference, more particularly to a novel door-knob, the spindle of which is of tubular construction provided with the knob attached thereto, with a key-operated mechanism for actuating a bolt, by means of which the door is ordinarily maintained in its closed position within the door-frame.

20 25 The present invention, therefore, has for its principal object to provide a novel and simply-constructed, as well as an effectively operating combination door-knob and lock, of the general character hereinafter more fully set forth, with a view of producing greater neatness in door-construction, owing to the fact that the usual door-locks and their escutcheon plates may be dispensed with.

30 35 Other objects of the present invention not at this time more particularly enumerated will be more fully set forth in the following specification.

With the various objects of the present invention in view, the said invention consists, 40 primarily, in the novel combination door-knob and lock hereinafter set forth; and, the said invention consists, furthermore, in the novel arrangements and combinations of the various devices and parts, as well as in the 45 details of the construction of the said parts, all of which will be more fully described in the following specification, and then finally embodied in the clauses of the claims which 50 are appended to and which form an essential part of the said specification.

The invention is illustrated in the accompanying drawings, in which:

55 Figure 1 is a front elevation of a door-knob made according to and embodying the

principles of the invention, showing in addition, in said view, fragmentary portions of a door and the door-frame; Figure 2 is a horizontal section of the same, said section being taken on line 2—2 in said Figure 1; 60 and Figure 3 is a vertical section, taken on line 3—3 in said Figure 1, the door-knobs and spindle of the device, however, being represented in elevation.

Figure 4 is a vertical sectional representation, taken on line 4—4 in Figure 3; Figure 5 is a horizontal sectional representation, taken on line 5—5 in Figure 2; and Figure 6 is a horizontal sectional representation, similar to Figure 2, the spindle and bolt-containing shell, however, being shown in elevation.

Figure 7 is a view similar to Figure 2, except that the various parts of the lock-mechanism are shown in elevation, with the 75 bolt represented in its unlocked relation with the key-operated mechanism of the device; and Figure 8 is a view similar to Figure 7, illustrating the various parts in their locked relation.

Figure 9 is a perspective view of the bolt employed with the device; and Figure 10 is a collective view, showing in elevation, portions of the spindle of the device.

Similar characters of reference are employed in all of the said above described views, to indicate corresponding parts.

Referring now to the said drawings, the reference-character 1 indicates a fragmentary portion of a door, and 2 a similar portion of the door-frame. As indicated in the several figures of the drawings, the door is provided with a socketed portion, as 3, usually of cylindrical cross-section, and with the laterally extending tubular portions 4 and 5, which communicate with said portion 3, substantially as shown. Suitably secured upon opposite sides of the door, by means of screws 6, or in any other suitable manner, are the usual rosettes 7 and 8, respectively 95 provided with the central openings 9 and 10 fitted in alinement with the respective tubular portions 4 and 5. As shown, the said rosettes 7 and 8 are also respectively provided with recessed portions 11 and 12, into 100 which are suitably fitted the shank-portions of suitably shaped door-knobs, as 13 and 14, substantially as shown in Figures 2, 3 and 6 of the drawings. These knobs are also of tubular structure, one tubular portion 15 of 105

each knob being preferably of larger cross-sectional area than the other tubular portion 16 of each knob.

The spindle of the combination door-knob 5 and lock comprises a main tubular member 17 of such length that its end-portions will extend into and through the respective rosettes 7 and 8, for mounting upon the projecting end-portions of said member 17, the 10 tubular shank-portions of the door-knobs 13 and 14, and for operatively securing the said door-knobs, by means of set-screws 18, or other suitable means, upon the respective end-portions of said member 17. In its opposite sides, and centrally disposed between the end-portions of the said member 17, the latter is formed with suitable openings or slots, as 19 and 20, and suitably fixed within said member 17, at desired locations, are 15 stops or retaining discs 21 and 22, provided with openings or perforations 23 and 24. Movably disposed within the said tubular member 17, between the said stops or retaining discs 21 and 22 is a lock-spindle receiving tubular element 25, the tubular portion or bore 26 of which is of a squared or similarly shaped cross-section. In its opposite sides the said element 25 is made with elongated openings 27 and 28, disposed in angular or helical relation across each other, substantially as represented in Figure 8 of the drawings. Concentric with the said member 17 is a tubular bolt-actuating member 29, with oppositely extending bolt-actuating 25 wings or fingers 30 and 31, and with perforations 32 and 33 in its opposite sides.

A pin 34 is employed in a manner as shown in Figures 2, 5 and 7, for maintaining the said members or elements 17, 25 40 and 29 in their assembled and operative relation.

Suitably secured within the tubular portion 15 of each door-knob is a cylindrical shell or casing 35, the outer end-portion of 45 each shell or casing being flush with the end-surface of the knob. Rotatably disposed within each shell or casing 35, and suitably maintained therein against displacement is a key-receiving barrel 36, provided 50 in its inner end-portion with a disc 37, or similar means, which is provided with openings or perforations, as 38, for the reception of the actuating lugs or teats 40 of a key 39, for actuating the said barrel in each door-knob, as will be understood from an 55 inspection of Figure 2 of the drawings. Connected with and extending from each disc 37 is a lock-spindle 41, the spindles corresponding in cross-section to the cross-section of the tubular portion or bore 26 of the inner tubular element 25, for operatively fitting the free end-portions of the respective lock-spindles 41 into the said tubular portion or bore 26, as indicated in said 60 Figure 2 of the drawings. In order that

there may be no lost motion or loose connection between these assembled parts, a coil-spring 42 may be employed, said spring encircling one of said spindles 41, and being arranged under compression between the 70 disc 22 and the inner end of the key-barrel containing shell or casing 35 of the door-knob 13, as shown.

Referring now more particularly to Figures 7 and 8 of the drawings, it will be seen 75 that the door 1 which is provided with a lateral bore 3 has snugly fitted and suitably secured therein a bolt-receiving shell or casing, as 42. Movably disposed within this shell or casing is a bolt-member 43, having a chamfered or other suitably formed latch-plate engaging end 44, adapted to enter a suitably formed latch-plate 45, or other suitable bolt-receiving means, with which the door-frame 2 is provided. Extending rearwardly from said bolt-member 43 is a plate 46, said plate at its inner end being forked or bifurcated, as at 47. Connected with the said members 47, are U-shaped receiving elements, as 48, for receiving therein the previously mentioned bolt-actuating wings or fingers 30 and 31, as shown in said Figure 8 of the drawings.

Also connected with the said elements 48 are rearwardly extending rods or pins 49, and forwardly projecting stop-members 50, and connected with the free ends of the said rods or pins 49 is a guiding disc 51. The inner end of the said bolt-receiving shell or casing 3 is marginally flanged, as at 52, and is provided with another disc 53. A compression spring 54 is placed between the said discs 51 and 53, as shown. In its opposite sides, the said shell or casing 3 is provided with suitable openings 55 and 56, the said openings being in alinement with the previously mentioned openings 4 and 5 in the door, as shown in the several figures of the drawings.

When the various devices and parts of the herein-above described lock-mechanism are in their assembled relations shown in Figures 2, 6 and 7 of the drawings, with the wings or fingers 30 and 31 withdrawn from the U-shaped receiving elements 48, and against the stop-members, then the various elements are in what may be termed their unlocked relation; in other words, when the knob is manipulated by turning in the usual manner, the various tubular elements 17, 25 and 29, with the wings or fingers 30 and 31 will also be turned, as indicated in Figure 5, so that the bolt will be withdrawn from the latch-plate 45, with the disc 51 being caused to assume the position shown in said Figure 5, and with the coils of the spring 54 more fully compressed between said disc 51 and the disc 53. As soon as the knob is released, the spring 54 again returns the bolt and the actuating 110 115 120 125 130

elements to their normal initial positions, as will be evident. Thus, the door may be readily opened and closed. To enable proper action of the wings or fingers, when turning, the said shell or casing 3 is also provided in its sides with other openings, as 57, the purposes of which will be self-evident, more particularly from an inspection of said Figure 5.

10 In order to lock the bolt-member 43 against movement, by inserting a key 39 into either door-knob, the lock-spindle can be properly turned, and acting as a key for the tubular member 25, will also turn the latter, with the pin 34 riding in the angularly disposed slots 27 and 28. Consequently the pin moves also in the longitudinally extending slots 19 and 20 of the tubular member 17, whereby a sliding movement of the tubular member 29 and its wings or fingers 30 and 31, longitudinally upon the member 17 will also be produced. This movement of the member 29 causes the wings or fingers 30 and 31 to ride directly 25 into the U-shaped receiving elements 48, into locked engagement therewith, so that the knobs can not be manipulated, and whereby the bolt-member will be maintained in its locked engagement with the latch- 30 plate 45, as will be evident. Consequently the closed door is also locked against opening.

From the foregoing description of the present invention, it will be fully understood, that I have produced a neat arrangement of locking mechanism for doors, combined directly with the door-knobs thereof, the mechanism being readily actuated by the insertion and turning of the key in 40 either knob.

I am fully aware that changes may be made in the general arrangements and combinations of the various devices and parts, as well as in the details of the construction 45 of the said parts, without departing from the scope of the present invention as set forth in the foregoing specification, and as defined in the clauses of the claims which are appended thereto. Hence, I do not limit 50 my present invention to the exact arrangements and combinations of the various devices and parts as described in the said specification, nor do I confine myself to the exact details of the construction of the said 55 parts, as illustrated in the accompanying drawings.

I claim:—

1. In a combination door-knob and lock, a door-knob, a tubular spindle extending from said knob, a bolt, means connected with said spindle for actuating said bolt, a tubular member oscillatorily disposed within said spindle, and a key-actuated mechanism within said knob for actuating 60 the tubular member within the spindle and

for thereby locking said bolt and the bolt-actuating means of the spindle against movement.

2. In a combination door-knob and lock, a door-knob, a tubular spindle extending 70 from said knob, a bolt, a tubular member slidably mounted upon the outside of said spindle, a bolt-actuating means connected with said slideable member for actuating said bolt, a tubular member oscillatorily disposed within said spindle, and a key-actuated mechanism within said knob for actuating the tubular member within the spindle and for thereby locking said bolt and the bolt-actuating means of said slideable member 75 against movement.

3. In a combination door-knob and lock, a door-knob, a tubular spindle extending from said knob, a bolt, a tubular member 80 slidably mounted upon the outside of said spindle, bolt-actuating fingers extending from said slideable member for actuating said bolt, a tubular member oscillatorily disposed within said spindle, and a key-actuated mechanism within said knob for 85 actuating the tubular member within the spindle and for thereby locking said bolt and the bolt-actuating fingers against movement.

4. In a combination door-knob and lock, a door-knob, a tubular spindle extending 90 from said knob, said spindle being provided in its opposite sides with longitudinally extending slots, a bolt, a tubular member slidably mounted upon the outside of said spindle, said member being provided in its opposite sides with perforations, a bolt-actuating means connected with said slideable member for actuating said bolt, a tubular member oscillatorily disposed within said spindle, 95

said latter member being provided in its opposite sides with helically disposed slots, a pin within said latter member, said pin extending through said helical slots, through the longitudinally extending slots of the tubular spindle, and into the perforations of 100 said slideable member, and a key-actuated mechanism within said knob for actuating the tubular member within the spindle and by means of said pin actuating said slideable member, and thereby locking said bolt and the bolt-actuating means of said slideable member against movement.

5. In a combination door-knob and lock, a door-knob, a tubular spindle extending 105 from said knob, said spindle being provided in its opposite sides with longitudinally extending slots, a bolt, a tubular member slidably mounted upon the outside of said spindle, said member being provided in its opposite sides with perforations, bolt-actuating fingers extending from said slideable member for actuating said bolt, a tubular member oscillatorily disposed within said 110 spindle, said latter member being provided 115

in its opposite sides with helically disposed slots, a pin within said latter member, said pin extending through said helical slots, through the longitudinally extending slots 5 of the tubular spindle, and into the perforations of said slidable member, and a key-actuated mechanism within said knob for actuating the tubular member within the spindle and by means of the pin actuating 10 said slidable member, and thereby locking said bolt and the bolt-actuating fingers against movement.

6. In a combination door-knob and lock, a door-knob, a spindle extending from said 15 knob, a bolt-containing shell, a bolt within said shell, a plate extending rearwardly from said bolt, receiving elements connected with said plate, means connected with said spindle for actuating said bolt, and a key- 20 actuated mechanism within said knob for moving said bolt-actuating means into said receiving elements to lock said bolt against movement.

7. In a combination door-knob and lock, 25 a door-knob, a spindle extending from said knob, a bolt-containing shell, a bolt within said shell, a plate extending rearwardly from said bolt, receiving elements connected with said plate, a tubular member slidably 30 mounted upon said spindle, a bolt actuating means connected with said slidable member for actuating said bolt, and a key-actuated mechanism within said knob for actuating said tubular member and moving said bolt- 35 actuating means into said receiving elements to lock said bolt against movement.

8. In a combination door-knob and lock, 40 a door-knob, a spindle extending from said knob, a bolt-containing shell, a bolt within said shell, a plate extending rearwardly from said bolt, receiving elements connected with said plate, a tubular member slidably 45 mounted upon said spindle, bolt-actuating fingers extending from said slidable member for actuating said bolt and a key-actuated mechanism within said knob for actuating said tubular member and moving said fingers into said receiving elements to lock 50 said bolt against movement.

55 9. In a combination door-knob, and lock, a door-knob, a spindle extending from said knob, a bolt-containing shell, a bolt within said shell, a plate extending rearwardly from said bolt, receiving elements connected with said plate, means connected with said spindle for actuating said bolt, a tubular member oscillatorily disposed within said spindle, and a key actuated mechanism within said knob for actuating the tubular member 60 within the spindle and moving said bolt-actuating means into said receiving elements to lock said bolt against movement.

65 10. In a combination door-knob and lock, a door-knob, a spindle extending from said knob, a bolt-containing shell, a bolt within

said shell, a plate extending rearwardly from said bolt, receiving elements connected with said plate, a tubular member oscillatorily disposed within said spindle, a tubular member slidably mounted upon said spindle, a bolt-actuating means connected with said slidable member for actuating said bolt, and a key-actuated mechanism within said knob for actuating said tubular member and moving said bolt-actuating means into 75 said receiving elements to lock said bolt against movement.

11. In a combination door-knob and lock, a door-knob, a spindle extending from said knob, a bolt-containing shell, a bolt within 80 said shell, a plate extending rearwardly from said bolt, receiving elements connected with said plate, a tubular member oscillatorily disposed within said spindle, a tubular member slidably mounted upon said spindle, bolt-actuating fingers extending from said slidable member for actuating said bolt, and a key-actuated mechanism within said knob for actuating said tubular member and moving said fingers into said 85 receiving elements to lock said bolt against movement.

12. In a combination door-knob and lock, a door-knob, a bolt-containing shell, a bolt within said shell, a plate extending rearwardly from said bolt, receiving elements connected with said plate, a tubular spindle extending from said knob, said spindle being provided in its opposite sides with longitudinally extending slots, a tubular member 100 slidably mounted upon the outside of said spindle, said member being provided in its opposite sides with perforations, a bolt-actuating means connected with said slidable member for actuating said bolt, a tubular member oscillatorily disposed within said spindle, said latter member being provided in its opposite sides with helically disposed slots, a pin within said latter member, said pin extending through said helical slots, through the longitudinally extending slots of the tubular spindle, and into the perforations of said slidable member, and a key-actuated mechanism within said knob for 105 actuating said tubular member within the spindle and by means of said pin actuating said slidable member, and thereby moving said bolt-actuating means into said receiving elements to lock said bolt against movement.

13. In a combination door-knob and lock, 110 a door-knob, a bolt-containing shell, a bolt within said shell, a plate extending rearwardly from said bolt, receiving elements connected with said plate, a tubular spindle extending from said knob, said spindle being provided in its opposite sides with longitudinally extending slots, a tubular member 115 slidably mounted upon the outside of said spindle, said member being provided in its opposite sides with perforations, bolt-actuat- 120 125 130

ing fingers extending from said slideable member for actuating said bolt, a tubular member oscillatorily disposed within said spindle, said latter member being provided in its opposite sides with helically disposed slots, a pin within said latter member, said pin extending through said helical slots, through the longitudinally extending slots of the tubular spindle, and into the perforations of said slideable member, and a key-actuated mechanism within said knob for actuating the tubular member within the spindle and by means of the pin actuating said slideable member, and thereby moving said bolt-actuating fingers into said receiving elements to lock said bolt against movement.

14. In a combination door-knob and lock, a door-knob, a spindle extending from said knob, a bolt-containing shell, a bolt within said shell, a plate extending rearwardly from said bolt, receiving elements connected with said plate, rods extending rearwardly from said receiving elements, stop-members projecting forwardly from said receiving elements, a guiding disc connected with said rods, a second disc within said shell, a coil-spring located between said discs, means connected with said spindle for actuating said bolt, and a key-actuated mechanism within said knob for moving said bolt-actuating means into said receiving elements to lock said bolt against movement.

15. In a combination door-knob and lock, a door-knob, a spindle extending from said knob, a bolt-containing shell, a bolt within said shell, a plate extending rearwardly from said bolt, receiving elements connected with said plate, rods extending rearwardly from said receiving elements, stop-members projecting forwardly from said receiving elements, a guiding disc connected with said rods, a second disc within said shell, a coil-spring located between said disc, a tubular member slidably mounted upon said spindle, a bolt-actuating means connected with said slideable member for actuating said bolt, and a key-actuated mechanism within said knob for actuating said tubular member and moving said bolt-actuating means into said receiving elements to lock said bolt against movement.

16. In a combination door-knob and lock, a door-knob, a spindle extending from said knob, a bolt-containing shell, a bolt within said shell, a plate extending rearwardly from said bolt, receiving elements connected with said plate, rods extending rearwardly from said receiving elements, stop-members projecting forwardly from said receiving elements, a guiding disc connected with said rods, a second disc within said shell, a coil-spring located between said discs, a tubular member slidably mounted upon said spindle, bolt-actuating fingers extending from said

slideable member for actuating said bolt, and a key-actuated mechanism within said knob for actuating said tubular member and moving said fingers into said receiving elements to lock said bolt against movement. 70

17. In a combination door-knob and lock, a door-knob, a spindle extending from said knob, a bolt-containing shell, a bolt within said shell, a plate extending rearwardly from said bolt, receiving elements connected with said plate, rods extending rearwardly from said receiving elements, stop-members projecting forwardly from said receiving elements, a guiding disc connected with said rods, a second disc within said shell, a coil-spring located between said discs, means connected with said spindle for actuating said bolt, a tubular member oscillatorily disposed within said spindle, and a key-actuated mechanism within said knob for actuating the tubular member within the spindle and moving said bolt-actuating means into said receiving elements to lock said bolt against movement. 80

18. In a combination door-knob and lock, a door-knob, a spindle extending from said knob, a bolt-containing shell, a bolt within said shell, a plate extending rearwardly from said bolt, receiving elements connected with said plate, rods extending rearwardly from said receiving elements, stop-members projecting forwardly from said receiving elements, a guiding disc connected with said rods, a second disc within said shell, a coil-spring located between said discs, a tubular member oscillatorily disposed within said spindle, a tubular member slidably mounted upon said spindle, a bolt-actuating means connected with said slideable member for actuating said bolt, and a key-actuated mechanism within said knob for actuating said tubular member within the spindle and for moving said slideable member, and the bolt-actuating means thereof into said receiving elements to lock said bolt against movement. 100

19. In a combination door-knob and lock, a door-knob, a spindle extending from said knob, a bolt-containing shell, a bolt within said shell, a plate extending rearwardly from said bolt, receiving elements connected with said plate, rods extending rearwardly from said receiving elements, stop-members projecting forwardly from said receiving elements, a guiding disc connected with said rods, a second disc within said shell, a coil-spring located between said discs, a tubular member oscillatorily disposed within said spindle, a tubular member slidably mounted upon said spindle, bolt-actuating fingers extending from said slideable member for actuating said bolt, and a key-actuated mechanism within said knob for actuating said tubular member within the spindle and for moving said slideable member, and the bolt- 125

actuating fingers thereof into said receiving elements to lock said bolt against movement.

20. In a combination door-knob and lock, 5 a door-knob, a bolt-containing shell, a bolt within said shell, a plate extending rearwardly from said bolt, receiving elements connected with said plate, rods extending rearwardly from said receiving elements, 10 20 stop-members projecting forwardly from said receiving elements, a guiding disc connected with said rods, a second disc within said shell, a coil-spring located between said discs, a tubular spindle extending from said 15 knob, said spindle being provided in its opposite sides with longitudinally extending slots, a tubular member slidably mounted upon the outside of said spindle, said member being provided in its opposite sides with 20 perforations, a bolt-actuating means connected with said slidable member for actuating said bolt, a tubular member oscillatory disposed within said spindle, said latter member being provided in its opposite sides 25 with helically disposed slots, a pin within said latter member, said pin extending through said helical slots, through the longitudinally extending slots of the tubular spindle, and into the perforations of said 30 slidable member, and a key-actuated mechanism within said knob for actuating said tubular member within the spindle and by means of said pin actuating said slidable member, and thereby moving said bolt-actuating 35 means into said receiving elements to lock said bolt against movement.

21. In a combination door-knob and lock,

a door-knob, a bolt-containing shell, a bolt within said shell, a plate extending rearwardly from said bolt, receiving elements 40 connected with said plate, rods extending rearwardly from said receiving elements, stop-members projecting forwardly from said receiving elements, a guiding disc connected with said rods, a second disc within said shell, a coil-spring located between said discs, a tubular spindle extending from said knob, said spindle being provided in its opposite sides with longitudinally extending 45 slots, a tubular member slidably mounted upon the outside of said spindle, said member being provided in its opposite sides with perforations, bolt-actuating fingers extending from said slidable member for actuating said bolt, a tubular member oscillatory disposed within said spindle, said latter member being provided in its opposite sides with helically disposed slots, a pin within said latter member, said pin extending through said helical slots, through the longitudinally extending slots of the tubular spindle, and into the perforations of said 50 slidable member, and a key-actuated mechanism within said knob for actuating the tubular member within the spindle and by means of the pin actuating said slidable member, and thereby moving said bolt-actuating fingers into said receiving elements to lock said bolt against movement.

In testimony that I claim the invention set forth above I have hereunto set my hand this 27th day of October, 1924.

JOSEPH SONNENBERG.
